UNITED STATES PATENT OFFICE.

CHARLES L. PLUNKETT, OF NEW YORK, N. Y., ASSIGNOR TO AMERICAN COUCH COMPANY, OF NEW YORK, N. Y., A CORPORATION OF NEW YORK.

COUCH OR COUCH-BED.

No. 815,118.

Specification of Letters Patent.

Patented March 13, 1906.

Application filed January 13, 1905. Serial No. 240,849.

To all whom it may concern:

Be it known that I, CHARLES L. PLUNKETT, a citizen of the United States, residing in the borough of Manhattan, city of New York, in the county of New York and State of New York, have invented certain new and useful Improvements in Couches or Couch-Beds, of which the following is a specification.

This invention relates to extension-couches or couch-beds, the object being to provide an improved extensible couch or couch-bed made up of a pair of improved sections, and in which the metallic fabric of one section will move between the metallic fabric and the side bar of the other section, so that when extended the two metallic fabrics will be nearly level to form an extensible or double bed, and which can be readily telescoped to form a single bed or couch.

20 A further object of the invention is the provision of an improved extensible couch or couch-bed made up of two sections, so assembled that one will be guided relatively to the other by improved guiding means which will not only facilitate the drawing out of the extensible section, but also act as means for maintaining the two sections permanently connected together against separation unless dismantled.

30 A further object of the invention is the provision of improved means for locking the two sections extended or closed.

A still further object of the invention is the provision of an extensible couch or couch-bed made up of a pair of improved sections, each of which is so constructed that it may be readily assembled by the retailer, to whom it may be shipped in a knockdown or dismantled condition, thus obviating the necessity of each being assembled, as heretofore, by the manufacturer and shipped in this condition to the retailer.

40 A further object of the invention is the provision of an improved couch-section which may be sold or used independently of or as a member of this improved extensible or sliding couch or couch-bed.

In the drawings accompanying and forming a part of this specification, Figure 1 is a 50 perspective view of this improved extensible couch or couch-bed, the extensible section being shown partly drawn out, a portion only of the metallic fabric being shown. Fig. 2 is a cross-sectional view of this improved extensible or sliding couch or couch-bed. Fig.

3 is a perspective view of one of the sections dismantled. Fig. 4 is a view of such section with all of its parts set up and fixedly connected, a portion only of the metallic fabric being shown, the dotted lines illustrating the 60 position of the end frames prior to the connection of the metallic fabric, and the full lines illustrating the end frames under the tension of the metallic fabric. Fig. 5 is a detail view of one of the socket members for the 65 reception of one end of a side bar. Fig. 6 is a different form of socket member used when the side bar is of tubular or round construction rather than of angle-iron. Figs. 7 and 8 are views of this improved locking device or 70 clamp, that shown in Fig. 7 being adapted for use with angle-iron side bars and that shown in Fig. 8 adapted for use with a tubular or round side bar.

Similar characters of reference designate 75 corresponding parts throughout the different figures of the drawings.

The present improvement comprises in the preferred form thereof herein shown and described a pair of improved sections A and B, 80 each comprising a pair of end frames 2 and 3, a pair of side bars 4 and 5, and stretchable flexible fabric—such, for instance, as a metallic fabric 6, stretched between such end frames—the organization being such that one 85 of the extensible sections B is slightly shorter and lower than the other, so that it will slide between the end frames with its metallic fabric between the metallic fabric and the side bar of the other or main section A, and thereby permit the metallic fabrics to be nearly 90 level when the sections are extended to form a double couch or couch-bed.

Each end frame comprises a pair of legs or feet 7 and a cross-bar 8, all of rigid construction and preferably integral, being usually made of one piece with the feet or legs bent at right angles to the cross-bar. When formed of angle-iron, apertures 9 are formed in the cross-bar for the reception of the ends 100 of the metallic fabric or mattress 6, usually for the reception of the ends of the spiral springs 4', to which the fabric of wire or otherwise is connected and which fabric is shorter than the couch, it being necessary to stretch 105 it in order to attach it to the cross-bars. When formed of tubular material, an angle-iron 10 is preferably riveted or otherwise secured to the tubular cross-bar of each end frame, and this iron provided with apertures 110

9 for the end of the metallic fabric, or these apertures may be formed directly in the tubular cross-bars. The side bars, which are held in position without rivets or other fastening means, project into suitable sockets 11, carried by the legs of the end frames, and for this purpose each leg is provided with a casting 12, secured thereon in any suitable manner, as by means of a pin or rivet, or chilled thereon, and which casting is provided with a suitable socket 11, according to the shape of the side bar that is to be used. In the form shown in Figs. 1, 2, and 5 this socket is shown as of V-shape formation for the reception of an angle-iron side bar 13, the apex 14 thereof being at the top whereby the side bars have greater strength and rigidity against buckling. Each casting may be formed with a suitable web 15, forming a brace or stiffening means. In the form shown in Fig. 6 the socket 11 is of tubular formation for the reception of a tubular or round side bar 16. In some forms of the structure, especially when it is desired to use a light side bar, a stay 17 is desirable, (see dotted lines, Fig. 4,) which, in the present instance, comprises a ribbon-like bar, the ends of which are riveted to the bar and form loops 18, such loops permitting the stay to be readily slipped on or off of the legs when the end frames are not connected by the metallic fabric.

For permanently connecting the two sections together when this is desirable, which, however, is not always the case, against separation without dismantling I have provided each end frame of the main section with a rod or bar 19, preferably located adjacent to the castings which receive the side bars, and for this purpose in the form shown each casting of the main section has its web 15 furnished with an opening 20, through which the rod 19 is passed, such rod having a head 21 at one end and a nut or other suitable clamping means 22 at the other end for rigidly securing it in position. The two castings of the extensible section carried by the two legs which run between the legs of the main section are provided on their outer sides with webs 23, having similar openings 24 in line with the openings in the webs of the main section, and through these two openings of the extensible section this rod 19 is passed before it is clamped in position. By this means the two sections are permanently connected together, so that they cannot be removed one from the other except by dismantling the main section. These rods will also act as braces for the main section and could also be used on the extensible section for the same purpose, (see dotted lines Fig. 4,) and especially is this desirable when the end frames are made of angle-iron. The castings may be formed as illustrated in Figs. 3, 5, and 6, if desired—that is, each casting may have a pair of webs provided with holes. In this manner any

casting could be placed on any leg without the necessity of particularly fitting the same, which is necessary when the castings are formed as shown in Fig. 1.

For clamping the two sections together when extended or when closed I have provided a suitable clamping means 30, which comprises two pairs of spring members 31, each pair secured intermediate their ends to the inner side bar of the extensible section B, and which members are bent to conform to the particular shape of the side bars. These members are secured, as stated, to the inner side bar of the extensible section and project in both directions, so that when the extensible section is nested the outer pair of arms of each clamping member will engage the outer side bar of the main section and when the section is extended the inner pair of arms of each clamping member will engage the inner side bar of such main section, thereby clamping the two sections in either their extended or closed position.

One of the important advantages of the present construction is that each section is made up of a pair of end frames, a pair of side bars, and a metallic fabric, the tension of which holds all the parts rigidly assembled without rivets or other similar fastening means and which can be readily assembled by the retailer instead of by the manufacturer, as has heretofore been necessary.

Heretofore it has been necessary for the manufacturer to assemble each section prior to shipment, since the parts were either so connected, as by rivets or otherwise, that the retailer could not do so, not having a machine-shop or the facilities to assemble the several parts, the expense of providing and maintaining such facilities being too great to warrant such an outlay.

In the present instance it will be noted that each frame comprises a pair of legs and a cross-bar, all bent from one piece of metal, and when made from angle-iron the holes for the mattress will be formed directly therein and when made of tubular stock an angle-iron member can be riveted by the manufacturer to the end frame. Each leg is then provided with a suitable casting either riveted or otherwise secured thereto, having a socket adapted to receive the end of a side bar which will conform to the shape of the socket in such casting. Thus, referring to Fig. 3, the two end frames, the two side bars, and the metallic fabric can be shipped in a knocked down or dismantled condition and in a much smaller space than heretofore, the result being a great saving in the cost of manufacture, in the cost of shipment, and in the handling at both ends of the sections of the bed. On their receipt in this condition by the retailer all that he needs to do is to insert the two side bars into the sockets of the two end frames, hook the metallic fabric into

one of the cross-bars of one of the end frames, take a button-hook and stretch and hook the other end of the metallic fabric into the apertures provided for that purpose in the other end frame, and which it has been demonstrated can be readily done notwithstanding the spiral springs of the metallic fabric are very powerful in their action, whereupon the section is complete and ready for use. One section is then inserted into position between the end frames with its metallic fabric between the side bar and the metallic fabric of the other section, the brace-rods, if these be used, slipped into position and clamped, and the bed is complete, and complete, as stated, at a great saving of time, labor, cost of production, and cost of shipment, enabling the bed to be made and sold at much less cost than heretofore. Of course it will be obvious that one of these sections could be used independently of its companion section, being readily shipped in the knocked-down condition hereinbefore set forth.

The rods at the ends of the bed will, as hereinbefore stated, act as braces or stays to prevent the spread of the legs under the weight of the body, and especially may this be desirable when the end frames are made of some kinds of angle-iron, although with other kinds of angle-iron and with tubular metal they need not be used. When assembled in the manner indicated by the retailer, it will be seen that the tension of the metallic fabric constitutes the means which rigidly and fixedly connects the two end frames of each section together in assembled set-up position with the two side bars in position, and that when this metallic fabric is removed the entire structure can be quickly dismantled, there being no rivets or other fastening means connecting the side bars rigidly or permanently with the end frames, as heretofore, so that the necessity of each section being properly assembled and permanently connected by the manufacturer before shipment is avoided.

In those structures where the stay-rods are used the retailer merely slips the looped ends thereof upon the legs below the side bars, inserts the side bars, and then connects the metallic fabric, the tension of the fabric drawing the stay taut and preventing the displacement thereof.

To compensate for any slight bending of the side bars, the sockets may be located at an angle less than a right angle—for instance, about eighty-eight degrees—to the castings or legs of the end frames, so that when the cross-bars of the end frames are drawn together under the tension of the metallic fabric the legs will be in a vertical position.

From the foregoing it will be seen that each couch section or bed is very simple in its formation, it comprising in its simplest form a pair of end frames, the legs of which may be

rigidly secured to the cross-bars or supports or integral therewith, usually being bent from a single piece, such pair of end frames being connected loosely—that is, separably—by a pair of rigid side bars or members, suitable means being provided to permit this, which means is shown in the present instance as castings secured to the legs of the end frames and having sockets into which the side bars project (a reversal of this might be adopted) and a stretchable metallic fabric shorter than the distance between the two end frames when properly set up, so that when stretched and connected to said end frames in any suitable manner the tension thereof will draw the two end frames together and rigidly and to all intents and purposes permanently connect the end frames and side bars in their assembled set-up position in substantially the same condition as though the parts were riveted together, and this without the use of rivets or other similar fastening means. Of course when two of these sections are to be used together to form an extensible or sliding couch-bed, and should it be desirable to provide a six-leg extensible couch-bed instead of eight-leg, one of the legs of each end frame of one section will be dispensed with; but such end frames will still be connected loosely—that is, separably—by a pair of side bars in a manner similar to that shown and described—that is, to the end frames.

The present structure has certain advantages over the ordinary sliding couch in that aside from the fact that it can be used either as a couch or as a single or double bed or readily separated to make two independent single couches or beds which can be used either in the same or different rooms it may be quickly taken apart by the owner—that is to say, the two sections may not only be disconnected from each other, but the component parts of each section may be readily separated—so that the two side bars and two end frames and the metallic fabric may be wrapped up in a small bundle and stowed away in a very small space, which cannot be done with the ordinary extensible or sliding couch or couch-bed or with either section thereof, and this is true whether the owner has two sections or only one in use.

Having thus described my invention, I claim—

1. An extensible or sliding couch-bed, comprising a pair of sections nesting transversely one under the other, each such section comprising a pair of end frames, a pair of rigid side bars or members loosely or separably connected with said end frames, a flexible fabric shorter than the distance between said end frames when the latter, together with its side bars, are properly assembled and set up, and stretchable between and attachable to said end frames, so that all of such parts are re-

tained in assembled rigid position by the tension of the fabric, and means connecting said end frames below said side bars to prevent the spreading of the end frames under the 5 tension of the fabric.

2. An extensible or sliding couch-bed, comprising a pair of nested sections, each section comprising a pair of end frames, a pair of rigid side bars or members loosely or separably connected with said end frames, a metallic fabric shorter than the distance between said end frames when the latter, together with its side bars, are properly assembled and set up, and stretchable between and attachable to said end frames, so that all of said parts are retained in assembled rigid alinement by the tension of the fabric, and means for connecting the end frames together below the side bars to prevent the spreading 15 of the end frames under the tension of the fabric, the metallic fabric of one section movable transversely between a side bar and the metallic fabric of the other section.

3. An extensible couch-bed, comprising a 25 pair of nested sections, each comprising a pair of integrally-formed bent end frames, a pair of side bars, and a pair of stays, all separably or loosely connected, said stays connecting the end frames below said side bars 30 to prevent the spreading of the end frames under the tension of the fabric, and a metallic fabric connecting said end frames; the tension of said fabric maintaining all of such parts together in rigid alinement without rivets or other fastening means, and the metallic fabric of one section movable between a side bar and the metallic fabric of the other section.

4. An extensible or sliding couch-bed, comprising a pair of transversely-nesting sections, each made up of a pair of end frames comprising a pair of legs or feet and a cross-bar rigidly connected, a pair of rigid side bars or members loosely or separably connected 45 with said end frames, a metallic fabric shorter than the distance between said end frames when the latter, together with its side bars, are properly assembled and set up, and stretchable between and attachable to said 50 end frames, so that all of such parts are retained in assembled rigid alinement by the tension of the fabric, and a pair of stays in position on the feet of the end frames below the side bars to prevent the spreading of such 55 end frames under the tension of the fabric.

5. An extensible couch or couch-bed comprising a pair of sections nested so that a metallic fabric of one section will run between a side bar and the metallic fabric of the other section, and each comprising a pair of end frames each of integral construction and consisting of a pair of legs and a cross-bar, a side-bar-receiving means carried by each leg, a pair of side bars, stays stretched between 60 said legs below said side bars, and a metallic

fabric stretched between said cross-bars, the tension of the metallic fabric fixedly connecting all said parts rigidly together without rivets or other similar fastening means.

6. An extensible couch or couch-bed comprising a pair of sections nested so that a metallic fabric of one section will run between a side bar and the metallic fabric of the other section, and each section comprising a pair of end frames each of integral construction and 75 consisting of a pair of legs and a cross-bar, a side-bar-receiving means carried by each leg, a pair of side bars, and a metallic fabric stretched between said cross-bars, the tension of the metallic fabric fixedly connecting 80 all of said parts rigidly together, and a brace-rod connecting the legs of each end frame of the main section together, and such main section permanently with the extensible section.

7. An extensible couch or couch-bed comprising a pair of sections each composed of a pair of end frames, a pair of side bars and a metallic mattress stretched between such end frames, a rod connecting the two legs of each 90 end frame of the main section together, and the main section with the extensible section, whereby the sections are not separable except on the dismantling of one of the sections.

8. An extensible couch or couch-bed comprising a pair of nested sections, each comprising a pair of end frames, a pair of side bars, and a metallic mattress stretched between such end frames, the metallic mattress of one section running between the metallic mattress and a side bar of the other section, and rods or bars running through openings in the extensible section for locking the two sections against separation except on the dismantling of one of them.

9. An extensible couch or couch-bed comprising a pair of sections each comprising a pair of end frames, a pair of side bars, and a metallic mattress stretched between such end frames, the metallic mattress of one section running between the metallic mattress and a side bar of the other section, each leg of the main section having a part provided with an opening, the inner legs of the extensible section also having a part provided with an opening in register with the openings of the main section, and a rod passing through said openings and secured in position and forming a guide for the extensible section.

10. An extensible couch or couch-bed comprising a pair of nested sections each comprising a pair of end frames and a pair of side bars with a metallic mattress stretched between said end frames, and clamping means 125 comprising spring-arms carried by the inner side bar of the extensible section, and effective to clamp the side bars of the main section in either the extended or closed position of the extensible section.

11. An extensible couch or couch-bed comprising a pair of nested sections each comprising a pair of end frames and a pair of side bars with a metallic mattress stretched between said end frames, and clamping means comprising spring-arms carried by a part of said extensible section and effective to clamp a part of the main section in either the extended or closed position of the extensible section.

12. An extensible couch or couch-bed comprising a pair of nested sections each comprising a pair of end frames and a pair of side bars with a metallic mattress stretched between said end frames, and clamping means comprising spring-arms carried by the inner side bar of the extensible section and effective to clamp the side bars of the main section in either the extended or closed position of the extensible section, said spring-arms conforming to the shape of the side bars.

13. A couch made up of four legs, two side bars and two cross-bars, with a cross-bar connecting each pair of said legs to form an end frame and the side bars connecting such end frames together, two of said bars being permanently secured to said legs and the other two bars being loosely or separably connected thereto, so that each pair of bars will have fixedly connected therewith a pair of legs, a fabric shorter than the distance between said end frames when the latter, together with its side bars, are properly assembled and set up, and stretchable between and attachable to said end frames, so that all of said parts are maintained in rigid alinement by the tension of the fabric, and a pair of stays connecting said legs below the side bars to prevent the spreading of the legs under the tension of the fabric.

14. A couch-section, comprising a pair of end frames and a pair of side bars or members loosely or separably connected with said end frames, a flexible fabric shorter than the distance between said end frames when the latter, together with its side bars, are properly assembled and set up, and stretchable between and attachable to said end frames, so that all of said parts are retained in assembled rigid position by the tension of the fabric, and means for tying the end frames together below the side bars to prevent the spreading of the end frames under the tension of the fabric.

15. A couch-section comprising two end frames each consisting of a pair of legs and a cross-bar rigid therewith and forming the tie between said legs and having means for the reception of the end of a fabric, each end frame forming a permanent structure, each leg of which is provided with a cast-socket for the reception of a side bar, a pair of side bars, and a fabric stretched between said cross-bars the tension thereof fixedly connecting the end frames and the side bars

rigidly together, and stays connecting the legs of the two end frames, all said parts being assembled as an article of manufacture without the use of rivets or bolts.

16. A couch-section, comprising a pair of end frames, each bent from a single member to form a pair of integral feet and a cross-bar, a pair of side bars loosely or separably connected with said end frames, a metallic fabric shorter than the distance between said end frames when the latter, together with its side bars, are properly assembled and set up, and stretchable between and attachable to the end frames, so that such end frames and side bars are maintained in assembled rigid alinement by the tension of the fabric, and stays connecting the feet of the end frames below the side bars to prevent the spreading of the end frames under the tension of the fabric.

17. A couch-section, comprising a pair of end frames, each comprising a cross-bar and a pair of legs or feet, a pair of rigid side bars loosely or separably connected with said feet, a metallic fabric shorter than the distance between said end frames when the latter, together with its side bars, are properly assembled and set up, and stretchable between and attachable to said cross-bars, so that all of said parts are retained in rigid alinement by the tension of the fabric, the connection between said end frames and side bars being such that they are inseparable until the fabric is first removed from the end frames, and a pair of stays attached to the feet of said end frames below the side bars to prevent the spreading of the end frames under the tension of the fabric.

18. The combination of a couch-section comprising a pair of end frames each bent from a single member to form a pair of legs and a cross-bar, said cross-bar having means for the connection of one end of a metallic fabric, and each leg having means for the reception of one end of a side bar, a pair of side bars and a metallic fabric stretched between said cross-bars and fixedly connecting the end frames and side bars in rigid position, a companion section made in a similar manner, said sections being nested so that the metallic fabric of one will run between a side bar and the metallic fabric of the other, whereby the metallic fabric will be nearly level when extended, and means for permanently connecting said sections together against separation without dismantling, said means comprising a pair of rods connected one with the legs of each end frame of the main section and with a pair of end frames of the other section.

Signed at Nos. 9 to 15 Murray street, New York, N. Y., this 7th day of January, 1905.

CHARLES L. PLUNKETT.
